CLAIM

The ornamental design for a gasification device, as shown and described.

DESCRIPTION

FIG. 1 is a front, top perspective view of a gasification device showing the new design;

FIG. 2 is a rear, bottom perspective view thereof;

FIG. 3 is a front elevation view thereof;

FIG. 4 is a left side elevation view thereof, the right side elevation view being identical thereto;

FIG. 5 is a rear elevation view thereof;

FIG. 6 is a top plan view thereof; and,

FIG. 7 is a bottom plan view thereof.

The broken lines shown in the drawings illustrate portions of the gasification device that form no part of the claimed design.
